UNITED STATES PATENT OFFICE.

LESLIE B. WOODRUFF AND FRED E. CATON, OF SAN JOSE, CALIFORNIA.

INKING APPARATUS.

SPECIFICATION forming part of Letters Patent No. 705,184, dated July 22, 1902.

Application filed March 12, 1902. Serial No. 97,806. (No model.)

To all whom it may concern:

Be it known that we, LESLIE B. WOODRUFF and FRED E. CATON, citizens of the United States, residing at San Jose, Santa Clara county, State of California, have invented certain new and useful Improvements in Inking Apparatus; and we do hereby declare the following to be a full, clear, and exact description of the same.

10 Our invention relates to that class of inking apparatus in which an ink-supply device of suitable character is located in proximity to the type-form to be inked, and an independent manually-operated form-inking roller defining its ink-supply by contact with the supply device is lifted or moved bodily by the operator forth and back between said supply device and the type-form. This style of inking apparatus is used in connection with hand 15 printing-presses, in which the type-form is exposed to be inked either by being moved back and forth to alternately receive its ink and to make its impression or by the completion of the stroke of an impression-cylinder 20 rolled over it.

The inking apparatus in one of its usual forms consists of a stand or frame adapted to be set in proximity to the bed of the press upon which the type-form is exposed to be 25 inked, said frame carrying in its top a pair of ink-supply rollers, usually made of wood and one having a crank for turning them. An independent form-inking roller carried in a handled bail is by the operator alternately 30 passed over and in contact with the ink-supply rollers and with the type-form, the operator turning the supply-rollers with one hand whenever the ink is required to be distributed or spread evenly and then bodily lifting or 35 moving the form-inking roller forth and back between the supply-rollers and the type-form. This lifting or moving of the form-inking roller as is usually done has, among others, the following objections, to wit: First, unless 40 performed with great care, involving loss of time, the exposed edges of the chase are inked, causing it to soil the sheet to be printed; second, if an ink plate or apron is used, over 45 which the inking-roller passes between the supply-rollers and the type-form, part of the ink is left on the plate, causing an uneven appearance of the printing; third, the lifting or

5 moving of the inking-roller is a severe tax upon the strength of the operator, not so much because of the weight to be lifted as 55 because of the prolongation of the operation or, if an ink plate or apron be used, because of the natural cohesion of the inking-roller to said plate or apron.

The objects of our invention are to avoid 60 inking the chase, to secure uniformity in inking the forms, to relieve the tax upon the strength of the operator, and to make the movement uniformly accurate and easily performed.

65 To these ends our invention consists, essentially, in a movable oscillating or reciprocating carrier so disposed as to receive the form-inking roller from the ink-supply device and to transfer it under the guidance of the 70 operator and with precision to the type-form and to again receive it from the type-form and bear it back again to the supply device.

75 Our invention further consists in the novel disposition and arrangement of the carrier, as we shall now describe by reference to the accompanying drawings, in which—

Figure 1 is a side view of our inking apparatus, showing one form of our carrier and showing also by dotted lines the different positions of the carrier and those of the inking-roller. Fig. 2 is a top view of the apparatus of Fig. 1, showing the inking-roller on the type-form and the carrier down in position on the chase containing the form and waiting 85 to receive said roller to transfer it back again to the ink-supply rollers. Fig. 3 is a side view showing another form of our inking apparatus and carrier and its application to the type-bed. Fig. 4 is a top view of same.

90 A is the type-bed of a printing-press, upon which lies the type-form B, and C is the chase holding the form.

D is the ink-supply device, which may be of any suitable character. It is here shown 95 in the form of two rollers, one roller being provided with a crank d for turning it. E is the form-inking roller carried by a bail e, provided with handle e'. These ink-supply rollers are to be placed in convenient proximity 100 to the type-bed A to enable the inking-roller to be transferred forth and back between the type-form and the supply-rollers. It is immaterial as far as the essential feature of our

invention is concerned what kind of a frame carries these supply-rollers or other inking device or whether said frame is attached to or is independent of the type-bed A or stand 5 of the press or, if attached, what kind of a connection is made. For the purposes of illustration we have shown one kind of frame in Figs. 1 and 2 and another kind in Figs. 3 and 4. In Figs. 1 and 2 we show the application of our invention to a common form of inking apparatus of this class consisting of the frame as an independent stand F, which carries the ink-supply rollers in its top and which is adapted to be adjusted to its proper 15 place relatively to the type-bed on which the type-form rests.

In Figs. 3 and 4 we show a bracket-frame F', carrying the ink-supply rollers and adapted to be secured, as by the bolts f', to the 20 frame of the type-bed.

Our ink-roller carrier may be of any suitable shape or construction and may be connected with the stand F or bracket-frame F' in any suitable manner. Its chief essential 25 is its adaptability to receive and bear the weight of the inking-roller and to transfer it from the ink-supply device to the type-form and back again. It may be an open or closed framework or a pair or series of arms and of 30 suitable cross-section and length. The form of carrier G shown in Figs. 1 and 2 is a trough of the length of the ink-supply rollers, thereby adapting it to receive and hold the form-inking roller irrespective of the length 35 of the latter, so that rollers of different lengths may be used without adjustment. The form shown in Figs. 3 and 4 is the concaved ends or heads G' of a pair of arms H', which said ends or heads are adapted to receive the ends 40 e² of the form-inking roller.

The ink-roller carrier is a movable one, having a travel between the ink-supply rollers and the type-form. Its movement is such as to carry it at one limit into such position relatively to the supply-rollers as to allow the form-inking roller to be rolled directly from 45 said rollers into said carrier, and at the other limit it will lie in such position as to permit the form-inking roller to be rolled out of it 50 upon the type-form. The adjustment of the movement is such that at its forward limit the carrier lies over and protects the chase C, so that the inking-roller will pass directly upon the form without contact with the chase. 55 To effect this movement, the carrier may be mounted in any suitable manner. That which we show in Figs. 1 and 2 consists of end links or arms H, connected with it and pivoted at their lower ends to suitable brackets f on 60 stand F. The center of movement is slightly forward of the rear limit of the carrier, so that said carrier will lie at rest against the edge of the frame in which the supply-rollers are journaled and be ready to receive the 65 inking-roller, as seen in Fig. 1. It will be observed that the carrier G of Figs. 1 and 2 is secured to its arms H by bolts g. By loosen-

ing these bolts the carrier may be turned slightly to vary its position relatively to the arms, and thus it may be adjusted readily to 70 lie in the proper position both to receive the inking-roller and to lie on the chase without striking or resting on the type-form.

The form of carrier connection which we show in Figs. 3 and 4 consists of the pair of 75 arms H', secured upon a squared rock-shaft h', whereby said arms swing in unison, with the rock-shaft, which is journaled in the bracket-frame F', for a center. To provide for different lengths of form-inking rollers, 80 the arms H' may be secured upon the rock-shaft h' adjustably, so that they may slide closer together or farther apart, and be fixed in position where adjusted by set-screws h². The form of carrier G' of Figs. 3 and 4 by not 85 coming into contact with the inked surface of the inking-roller will avoid any tendency to disturb said surface.

The operation is as follows: The operator grasping handle e holds the form-inking roller, 90 presses it forward, and rolls it into the waiting carrier. Then with the inking-roller lying in the carrier he pushes on the handle e, and thereby swings the carrier containing the inking-roller forward until the carrier 95 reaches the chase at the edge of the form. Then he pushes the inking-roller out of the carrier, upon and over the type-form B, and when the latter is inked he draws the inking-roller back into the carrier. Thereupon he draws 100 on the handle e, and thus swings the carrier, with its contained inking-roller, back to its first position, and finally he draws the inking-roller out of the carrier to and upon the supply-rollers. 105

Although the description of the movement of the inking-roller here given indicates a number of impulses in broken movements, in practice this is not the case, for by pressing forward on the inking-roller it is easily and naturally rolled from the supply-rollers into the carrier and to the type-form by one continuous motion, and the same movement is obtained when the inking-roller is returned from the type-form to the supply-rollers. 115 Thus the operator is relieved of the weight and suction of the inking-roller, and said roller is carried with precision between its limits of operation.

Having thus described our invention, what 120 we claim as new, and desire to secure by Letters Patent, is—

1. In an inking apparatus having an ink-supply device and an independent, manually-operated form-inking roller, deriving its ink-supply by contact with said supply device, a 125 movable carrier adapted to travel between the ink-supply device and the type-form, and disposed to receive the form-inking roller from the supply device and to transfer it under the 130 guidance of the operator to the type-form and back again.

2. In an inking apparatus comprising a frame, an ink-supply device carried thereby,

and an independent manually-operated form-inking roller deriving its ink-supply by contact with said supply device, a carrier movably connected with said frame and disposed to receive the form-inking roller from the supply device and to transfer it under the guidance of the operator to the type-form and back again.

3. In an inking apparatus comprising a frame, an ink-supply device carried thereby and an independent manually-operated form-inking roller deriving its ink-supply by contact with said supply device, a carrier pivotally connected with said frame adapting it to swing between the ink-supply device and the type-form and so disposed as to receive the form-inking roller from the ink-supply device and to transfer it under the guidance of the operator to the type-form and back again.
4. An inking apparatus comprising a frame, an ink-supply device carried thereby, an independent manually-operated form-inking roller deriving its ink-supply by contact with said supply device, a carrier adapted to receive the inking-roller from the supply device and pivoted arms connecting the carrier with the frame adapting said carrier to swing between the ink-supply device and the type-form, whereby said carrier is adapted to transfer the form-inking roller, under the guidance of the operator, from the ink-supply device to the type-form and back again.
5. An inking apparatus comprising a frame,

an ink-supply device carried thereby and an independent manually-operated form-inking roller deriving its ink-supply by contact with said supply device and an adjustable carrier pivotally connected with said frame adapting it to swing between the ink-supply device and the type-form and so disposed as to receive the form-inking roller from the supply device and to transfer it under the guidance of the operator to the type-form and back again.

6. An inking apparatus comprising a frame, an ink-supply device carried thereby, an independent manually-operated form-inking roller deriving its ink-supply by contact with said supply device, a carrier adapted to receive the inking-roller from the supply device, pivoted arms connecting the carrier with the frame and adapting said carrier to swing between the ink-supply device and the type-form whereby said carrier is adapted to transfer the form-inking roller, under the guidance of the operator, from the ink-supply device to the type-form and back again, and a connection between the carrier and said arms whereby the carrier can be adjusted relatively thereto.

In witness whereof we have hereunto set our hands.
